US00D727935S

(12) **United States Design Patent**
Myette et al.

(10) **Patent No.:** US D727,935 S
(45) **Date of Patent:** ** Apr. 28, 2015

(54) **DISPLAY SCREEN WITH GRAPHICAL USER INTERFACE**

(71) Applicant: **Microsoft Corporation**, Redmond, WA (US)

(72) Inventors: **Jon Nicolas Myette**, Seattle, WA (US); **Gautam Satalkar**, San Jose, CA (US); **Gaurang Prajapati**, Redmond, WA (US); **Peyu Liu**, Seattle, WA (US)

(73) Assignee: **Microsoft Corporation**, Redmond, WA (US)

(**) Term: **14 Years**

(21) Appl. No.: **29/436,554**

(22) Filed: **Nov. 7, 2012**

(51) LOC (10) Cl. **14-04**

(52) U.S. Cl. **USPC** **D14/486**

(58) **Field of Classification Search**

(74) *Attorney, Agent, or Firm* — Banner & Witcoff, Ltd.

(57) **CLAIM**

The ornamental design for a display screen with graphical user interface, as shown and described.

DESCRIPTION

The FIGURE is a front view of a display screen with graphical user interface showing our new design.

The broken line showing of the text and the remainder of the user interface and display screen is for environmental purposes only and forms no part of the claimed design.

1 Claim, 1 Drawing Sheet
